CLAIM

The ornamental design for a LED illuminator, as shown and described.

DESCRIPTION

FIG. 1 is a left front perspective view of the LED illuminator of the present invention;

FIG. 2 is a right side elevation view of the LED illuminator of the present invention;

FIG. 3 is a left side elevation view of the LED illuminator of the present invention;

FIG. 4 is a front elevation view of the LED illuminator of the present invention;

FIG. 5 is a rear elevation view of the LED illuminator of the present invention;

FIG. 6 is a top plan view of the LED illuminator of the present invention; and,

FIG. 7 is a bottom plan view of the LED illuminator of the present invention.

The portions of the drawing shown in broken lines form no part of the design sought to be patented.
